G. H. TAYLOR.

RUCHING.

No. 17,010.

Patented Nov. 30, 1881

UNITED STATES PATENT OFFICE.

GEORGE H. TAYLOR, OF NEW YORK, N. Y., ASSIGNOR TO THE KURSHEEDT MANUFACTURING COMPANY, OF SAME PLACE.

DESIGN FOR RUCHING.

SPECIFICATION forming part of Design No. 17,010, dated November 30, 1886.

Application filed September 2, 1886. Serial No. 212,563. Term of patent 7½ years.

To all whom it may concern:

Be it known that I, GEORGE H. TAYLOR, a resident of New York city, in the county and State of New York, have invented and produced a new and original Design for Neck-Ruching, of which the following is a full, clear, and exact description, reference being made to the accompanying photograph, which represents my new design for neck ruching.

10 This invention relates to a new configuration of neck-ruching for ladies.

In the accompanying photograph, the letter *a* represents the band that carries the new design for ruching. From this band extend loops *b* into the valleys of the undulation of the corrugated or scalloped body *c*, so that said

body *c* extends to a greater distance from the band *a* between the loops *b* than it does in said loops. *d* is a fluted backing which extends beyond the looped body *c*.

20

I claim—

1. The design for a ruching, the same consisting of the corrugated or scalloped body *c* and loops *b* in the valleys of the undulations of the body *c*, substantially as shown.

25

2. The design for a ruching, the same consisting of the loops *b*, corrugated body *c*, and fluted backing *d*, substantially as shown.

GEORGE H. TAYLOR.

Witnesses:

CHARLES G. M. THOMAS,

HARRY M. TURK.
